UNITED STATES PATENT OFFICE.

PAUL J. GRINBERG, OF NEW YORK, N. Y.

WICK-TUBE.

SPECIFICATION forming part of Letters Patent No. 431,577, dated July 8, 1890.

Application filed March 28, 1890. Serial No. 345,647. (No model.)

To all whom it may concern:

Be it known that I, PAUL J. GRINBERG, of New York city, New York, have invented an Improved Wick-Tube, of which the following

5 is a specification.

This invention relates to a wick-tube for oil-stoves, so constructed that the tubular bearings for the wick-raising shaft are formed directly upon the housing. To this effect the 10 housing is struck up together with the bearings, and is then soldered over a slot in the wick-tube proper.

The invention consists in the various features of improvement more fully pointed out 15 in the claims.

In the accompanying drawings, Figure 1 is a face view of the housing detached; Fig. 2, a side view at right angles to Fig. 1; Fig. 3, a face view of the blank for forming the wick- 20 tube before being bent; Fig. 4, an edge view thereof; Fig. 5, a vertical longitudinal section of the completed wick-tube with the housing and wick-raiser in place; Fig. 6, a side view of the completed wick-tube; Fig. 7, an end view 25 of the housing with the wick-raiser in place; Fig. 8, a side view of a portion of a housing, showing a modification; and Fig. 9, an end view thereof.

The letter *a* represents a rectangular sheet 30 of metal adapted to be bent upon the dotted double lines shown in Fig. 3, so as to constitute the wick-tube. The free ends of the wick-tube are connected by the lap-joint shown in Fig. 5, and thus the entire wick- 35 tube is formed from one continuous piece of sheet metal. Within one section of the wick-tube *a* there is cut a longitudinal slot *a'*, over which the housing is subsequently attached. Through this opening the wick-raiser, turning 40 within the housing, reaches the wick. The two short sides of opening *a'* are punched out to form four lugs *a²*, and between them the bearings *a³*. These bearings subsequently receive the wick-raising shaft. The lugs *a²* are 45 bent outward at right angles, so as to subsequently enter the housing, Fig. 5.

The housing *b* is struck up in a die from a rectangular piece of sheet metal, so as to as-

sume the usual trough shape. At its ends, however, there are struck up simultaneously with 50 the housing the semi-tubular bearings *b'*, as shown.

In putting the device together the wick-raising shaft *c* is slipped into bearings *a³*, and then the housing is soldered against the wick-tube, so as to close the opening *a'*, and of course to inclose the lugs *a²* and bearings *a³*. The two semi-tubular bearings *b'* will embrace the shaft *c* beyond the bearings *a³* to conceal the lugs *a²* and form the proper finish. 60

In Fig. 8 one of tubes *b'* is somewhat lengthened, and is provided at its ends with downwardly-depending lugs *b²*. These lugs project beyond the edge of the wick-tube *a*, after the housing has been soldered to such wick- 65 tube, and may be coiled around the shaft *c*, as shown in Fig. 9, to form a complete circular bearing.

The advantage of my improved wick-tube is that the bearings *b'* may be formed in one 70 operation with and directly upon the housing *b*. Moreover, the worm *c'* on the star-wheels for raising the wick may be soldered to the shaft *c* before the shaft is put in place within the housing. The entire device, though simple, presents a perfect finish when completed. 75

What I claim is—

1. The combination of wick-tube *a*, having slot *a'*, and outwardly-bent lugs *a²*, with housing *b*, secured to the wick-tube over slot *a'*, 80 and with the wick-raiser *c*, received between lugs *a²*, substantially as specified.

2. The combination of slotted wick-tube *a*, having outwardly-bent lugs *a²*, with the housing *b*, having tubular bearings *b'*, and secured 85 to tube *a*, and with wick-raiser *c*, substantially as specified.

3. The combination of slotted wick-tube *a* with housing *b*, having semi-tubular bearings *b'* and lugs *b²*, and with the wick-raiser *c*, 90 around which said lugs are coiled, substantially as specified.

PAUL J. GRINBERG.
